Primary Examiner—Cathron C. Brooks

(57) **CLAIM**

The ornamental design for a dispensing nozzle, as shown and described.

DESCRIPTION

FIG. 1 is a left side elevation showing my new design; FIG. 2 is a top plan view;

FIG. 3 is a front elevational view;

FIG. 4 is a rear elevational view;

FIG. 5 is a right side elevational view; and,

FIG. 6 is a bottom plan view.

The broken line showing of internal nozzle elements is for illustrative purposes only and forms no part of the claimed design.
